RAIL ANCHOR

Albert F. Fifield, St. Catharines, Ontario, Canada, assignor to The American Fork & Hoe Company, Cleveland, Ohio, a corporation of Ohio

Application August 24, 1931, Serial No. 558,861

8 Claims. (Cl. 238—324)

My invention relates to rail anchors and relates more particularly to two-piece rail anchors, which, as is well known, commonly comprise two interlocked elements conjointly clamped onto a rail base, and one of which is engageable with a fixed portion of the railway road bed, such as a tie to restrain longitudinal creeping of the clamped rail relative to said tie or other fixed road bed part.

- 10 It has been previously proposed, as disclosed in the patent to Charles G. Ericson, No. 1,402,852, dated January 10, 1922, to provide a two-piece rail anchor comprising a jaw member made of cast metal adapted to embrace one flange of a rail base and having its back formed as a wedge, in cooperation with a steel bar forming a yoke adapted to span the rail base and provided with a hook at one end to embrace the jaw member and overhang the rail base and a hook at the 15 other end to engage the opposite rail base with the engaging surface of the jaw member and the upper part of said hook shaped to spread the hook when the hook and jaw member are moved transversely of the rail base, the first outwardly 20 and the latter inwardly, by suitably sloping the wedge surface portion of said jaw member.

Anchors of the above described Ericson type have come into wide spread use and have been very successful. However satisfactorily these 30 anchors may have been in part, they have not fulfilled all requirements for a relatively inexpensive highly efficient means for preventing creeping of railroad rails and among the objections had to such Ericson anchors are the following:

35 First, when cars of railroad trains traversing the rails become derailed, the relatively rigid unyielding cast shoes are engaged by the wheels of the derailed cars and the entire road bed is torn up and the damage to the cars and the road bed is very seriously increased over what would occur were such shoes not in place.

Second, the more practical commercial embodiments of the Ericson anchor have been expensive to manufacture and to maintain and are subject to considerable variation in manufacture, one from another.

Third, the "bite" of the anchor on the rail base flanges has not been achieved in anchors of this 50 form in as efficient a manner as is accomplished in other types of two-piece anchors, such for instance as the type exemplified by United States Letters Patent No. 1,682,370 to F. W. Cooper, dated August 28, 1928, which has also gone into 55 wide spread use, and which is not subject to the

above said first objection nor to the above said second objection.

An object therefore of my invention is to provide an improved two-piece anchor which is not subject to the above said first objection.

Another object of my invention is to provide an improved two-piece anchor which is not subjected to the above said second objection.

Another object of my invention is to provide an improved two-piece anchor which is not subject to the above said third objection.

Another object of my invention is to provide an improved two-piece anchor which is not subject to any of the above said enumerated objections.

Another object of my invention is to provide an anchor which is inexpensive to manufacture in quantities, and which will be highly efficient in use.

Another object of my invention is to provide an improved method of making a highly efficient rail anchor.

Another object of my invention is to provide an improved rail anchor made at least in part of a rolled section of steel.

Other objects of my invention and the invention itself will become apparent to those skilled in the art to which my invention appertains from the following description of an embodiment of my invention and in which description reference will be had to the accompanying drawings illustrating said embodiment, wherein:

Fig. 1 is a view showing an embodiment of my invention illustrated in side elevation applied to the rail base of a railroad rail shown in vertical transverse section;

Fig. 2 is a plan view of the embodiment illustrated in Fig. 1, the web of the rail being shown in horizontal transverse section;

Fig. 3 is an end elevational view of the embodiment and rail shown in the foregoing figures;

Fig. 4 is a side elevational view of a tie engaging clamping shoe comprising an element of the said embodiment;

Fig. 5 is an elevational view taken of a front face of the element of Fig. 4;

Fig. 6 is a view of the side opposite to that shown in Fig. 4 of the said element, the view being taken at right angles to the view of Fig. 5;

Fig. 7 is a plan view of the element of Figs. 4 to 6 inclusive;

Fig. 8 is a view similar to that of Fig. 1 except that the anchor of the foregoing figures is shown at a portion incompletely applied to the base of

the rail in an intermediate position taken during the placement thereon;

Fig. 9 is a sectional view taken transversely of the rail base on the line 9-9 of Fig. 2 showing 5 the anchor completely applied to the rail base;

Fig. 10 is a section taken on the line 10-10 of Fig. 2;

Figs. 11, 12, and the three figures 13, 14, and 15 show successive steps of process which may 10 be involved in the production of the element of Figs. 4 to 7 inclusive, when said element is produced according to my improved method therefor.

Referring now to the different figures of drawings illustrating a preferred embodiment of my invention, at 1, I show a tie engaging clamping shoe comprising the novel element of my invention, since the other cooperating element shown at 2 is a yoke member of the character and type 20 illustrated in the prior patent to C. G. Ericson, No. 1,402,852, patented January 10, 1922.

The element 1 is herein substituted for the so-called wedge member of the said Ericson patent, and differs therefrom in a number of important 25 particulars, whereby the functional attainments of the anchor of my invention considerably exceed those of the anchor of the said Ericson patent.

The clamping shoe 1 comprises a substantially 30 T-shaped tie engaging part 3, the web 4 of which is adapted to join the tie engaging part with the channel shaped part 5 which embraces the outer portion of the base of a road rail 6. The tie engaging part 3 comprises a pair of oppositely 35 extending flanges 7 and 8, the lower portions of which, shown at 7' and 8', being adapted for engagement with the railroad tie 9, and the upper portion of the flange 8 is notched inwardly toward the longitudinal middle of the tie engaging part, where the web 4 joins said part. The notch is shown best in Figs. 5, 6, 10 and 15, at 40 10, and provides the flange 8 with upper and lower jaws 11 and 12 adapted to make tightly gripping clamping contact with the divergent upper and lower surface of the rail base flange, to which the element 1 is affixed.

The upper and lower walls 13 and 14, respectively, of the channel portion 5 of the clamping shoe 1 are slightly divergent and relatively variably formed to effect first the proper clamping contact with the rail base flange to cooperate with the jaws 11 and 12, and to wedgingly receive the larger hooked end 15 of the yoke member 2, which is provided with a smaller hook 16 55 at its opposite end.

The intermediate portion of the yoke comprises a rail base bottom engaging portion 17 and a relatively offset portion 18 adapted to embracingly engage the wall 14 of the channel 5, which 60 intervenes between and spaces the said offset portion 18 of the yoke, and the bottom surface of the rail base as shown particularly in Figs. 1 and 9.

The shoe 1, illustrated per se in Figs. 4 to 7, 65 inclusive, is preferably formed by cutting sections from a beam section rolled to form substantially as shown in Fig. 12 in a rolling mill in relatively long lengths, whereby a plurality of sections *a* and *b*, substantially as shown by the dotted lines in Fig. 11, may be cut from the I-beam section, each having the form illustrated in Figs. 13 to 15, inclusive, wherein notches 10 are cut preferably at the same time as the sections *a* and *b* are cut from the length of I-beam section.

75 The notches 10 provide the jaws 11 and 12, Fig.

6, as before described for the shoe element of my improved rail anchor. The channel part 5 of the said shoe element is formed by folding the portion 5', of each of the sections *a* or *b*, to the channel form, as shown in Figs. 4 to 7, inclusive, there being preferably, however, a web portion 4 which is not so folded and which remains to interconnect the channel portion 5 with the flange portions 7 and 8, as shown and described.

Therefore following the form taken as illustrated in Figs. 13 to 15, the sections *a* and *b* are then given the ultimate form shown in Figs. 4 to 7, inclusive, wherein the channel 5, having the required rail base flange embracing and yoke hook receiving surfaces is joined by a web 4 to the 10 oppositely extending flanges 7 and 8.

In forming the walls 13 and 14 of the channel, surplus metal in the interconnecting web portion 4, such as shown at 19, are turned inwardly, and thereby produce a second channel extending 20 transversely to the channel 5 and intermediate the said channel and the said flanges 7 and 8, whereby considerable rigidity is imparted to the 25 said web portion of the shoe.

Said shoe element formed as described has the 30 channel portion 5 so positioned that its channel is in approximate alignment with the notch 10 in the flange portion 8. The interior walls of the channel are so formed that inwardly extending surfaces thereof disposed particularly at 35 20, 21 and 22 engage the rail base flange when the shoe is projected onto the flange with the notch 10 and the channel of the element 5 receiving the flange, the portion of the rail base flange 6 engaged by the portions 20, 21 and 22, respectively, being spaced longitudinally of the rail, whereby a substantially three-point contact is had between the clamping shoe and the rail base flange by clamping portions of the shoe substantially spaced from each other longitudinally of 40 the rail base.

Also other portions of the shoe shown at 20' and 22' preferably engage the bottom surface of the rail base after the shoe has been driven to its ultimate position on the base flange of the 45 rail.

In order to drive the shoe onto a rail base flange sufficient driving force must be exerted to resiliently distort the clamping shoe, because of the first engagement by the jaw portions 20, 50 21 and 22 of the shoe with the upper and lower surfaces of the rail base flange and the jaw surfaces 20' and 22' are so positioned slightly lower than the jaw surface 21 before distortion of the shoe by the driving on process, that only when the driving results in distortion of the anchor shoe, will the jaw surfaces 20' and 22' make engagement, but soon after such engagement is had, the drive-on step of the process is completed and the shoe will remain in tightly driven resiliently 60 maintained embracing contact on the rail base flange 6, biting firmly against the longitudinally spaced surfaces of the rail base, particularly at the points 20, 21 and 22 thereof alternately above and below the rail base in longitudinally spaced portions.

Following the application of the shoe element 1 to a rail base flange, as previously described, the shoe being applied to the base flange so that the tie engaging portions 7' and 8' engage the tie 9 70 substantially as shown in Figs. 1 to 3, inclusive, and in Figs 8 to 10, inclusive, the yoke 2 having its opposite ends bent in the form of hooks, as before described, as set forth in the aforesaid Ericson patent of the prior art, is placed on the 75

5 rail base by the successive steps illustrated in Figs. 8 and 9, wherein the larger hook 15 is first placed over the rail base flange 6 and the smaller hook 16 is then lifted upwardly over the edge of the rail base flange 6 by moving it in the direction of the arrow 23, Fig. 8 and then the entire yoke is moved laterally in the direction of the arrow 24, Fig. 9, so that the small hook 16 is tightly fitted into, embracing engagement with 10 the rail base flange 6 and the large hook being moved outwardly from the rail base flange 6, may then be moved longitudinally of the rail over the channel part 5 of the shoe.

15 Both hooked ends of the yoke are driven along the rail base until, because of the progressively increased divergence of the upper and lower surfaces of the channel walls 13 and 14, respectively, as indicated at 25, Fig. 4, a tight wedging engagement is had between the embracing hook 15 and the embraced channel part 5, which further resiliently distorts the walls of the channel increases the anchoring bite of the jaws 20, 21 and 22 of the shoe on the rail base flange 6.

20 The wedging action of the shoe and yoke is somewhat similar to that described in the aforesaid Ericson patent to which reference is hereby made, except that in the said Ericson patent the property of resiliency being substantially absent from the so-called wedge-shaped jaw member, the effective bite had by applicant's jaw member 25 is not present in the Ericson structure; and the intermediate outer wall of the channel portion of the shoe is preferably slightly bowed so as to provide a wedge surface between the points *x* and *y* and an inwardly extending portion between the points *x* and *z*, whereby the hook portion 15 of the yoke will be retained in its operative position as shown in Fig. 2 and in Fig. 3. The outwardly bowed form of the channel intermediate portion is best shown in Figs. 2 and 7. The compressive stress exerted by the yoke upon the shoe has a horizontal component exerted against the said intermediate bowed wall of the shoe channel portion, and a vertical component exerted against the jaws 13 and 14 of said channel. Both vertical and horizontal stresses result in slight yielding of the resilient channel and a more effective bite upon the rail face flange 6.

25 Having thus described my invention, I am aware that numerous and extensive departures may be made from the embodiment of my invention herein illustrated and described, but without departing from the spirit thereof.

I claim:

- 30 1. A two-piece rail anchor comprising a yoke element having an intermediate portion adapted to underlie the base of a rail and hooked ends, a shoe formed from a rolled steel T section comprising a tie engaging portion provided by the T head and comprising a substantially rigid notched portion and a channel shaped rail base flange embracing portion provided by folding over portions of the T leg, said last named portion being inherently resilient, the notched and channel portions providing upper and lower jaw portions engageable with the upper and lower surfaces of the rail base flange at points relatively longitudinally spaced along the rail base, said channel shaped portion adapted to be compressively embraced by one of the said yoke hooks.
- 35 2. A two-piece rail anchor comprising a yoke element having an intermediate portion adapted to underlie the base of a rail and hooked ends, a shoe formed from a rolled steel section and comprising a tie engaging portion and comprising a substantially rigid notched portion and a channel shaped rail base flange embracing portion, said last named portion being inherently resilient, the notched and channel portions providing upper and lower jaw portions engageable with the upper and lower surfaces of the rail base flange at points relatively longitudinally spaced along the rail base, said channel shaped portion adapted to be compressively embraced by one of the said yoke hooks.
- 40 3. A rail anchor having a substantially rigid notched portion and relatively longitudinally spaced therefrom, a shoe member comprising a horizontal substantially resilient channel portion, providing upper and lower walls effective as jaws, said jaws and said notched portion adapted to embrace one flange of a rail base and formed as a wedge, and a heavy bar of metal acting as a yoke adapted to span the rail base having a hook at one end to engage one edge of said base, and a relatively rigid hook at its other end embracing said channel, said last-named hook compressively engaging said jaws to cause them to resiliently yield to effect a resilient bite onto the upper and lower surfaces of the said rail base flange in at least three longitudinally spaced points.
- 45 4. A rail anchor substantially constructed as set forth in claim 3 in which the upper and lower surfaces of the channel are substantially parallel for the greater part of their length and are slightly chamfered at the free end of the channel to facilitate its entry between the parts of the hook, and formed with inner surface portions spaced longitudinally of the rail base which engage the rail base flange on either side of said hook, the intermediate portions of the jaws being relieved from contact with said flange.
- 50 5. A rail anchor comprising a shoe member having a horizontal substantially resilient channel portion and a substantially rigid tie-engaging portion integrally formed therewith and provided with a notch portion longitudinally spaced from the channel portion, said portion being of substantially uniform thickness and formed of a single piece of rolled steel section, the tie-engaging portion extending in a plane at substantially right angles to the plane of the channel portion, said channel portion and notched portion providing a pair of upper and lower jaws adapted to embrace a rail base flange, a bar comprising a yoke formed with hooks at its two ends, one of said hooks adapted to engage one edge of the rail base, the other hook embracing the said channel portion of said shoe, and compressively forcing its upper and lower walls into resiliently maintained compressive engagement with the upper and lower surfaces of the other edge of the rail base, said channel being relieved from engagement with said rail base in intermediate portions and said channel-embracing hook engaging the channel over said relieved portion.
- 55 6. A rail anchor constructed substantially as set forth in claim 5 wherein the channel portion is provided with an intermediate rear wall which is bowed outwardly in a direction longitudinally of the rail base to facilitate entry of the hook over the channel portion and to effect retention thereof thereon when said hook has been driven past the most outwardly extending portion thereof.

7. A rail anchor comprising a shoe member having a horizontal substantially resilient channel portion and a tie-engaging portion integrally formed therewith, said portion being of substantially uniform thickness and formed of a single piece of rolled steel section, the tie-engaging portion extending in a plane at substantially right angles to the plane of the channel portion, said channel portion providing a pair of substantially resilient upper and lower jaws adapted to embrace a rail base flange, a bar comprising a yoke formed with hooks at its two ends, one of said hooks adapted to engage one edge of the rail base, the other hook embracing the said channel portion of said shoe, and compressively forcing its upper and lower walls into resiliently maintained compressive engagement with the upper and lower surfaces of the other edge of the rail base, said channel being relieved from engagement with said rail base in intermediate portions and said channel-embracing hook engaging the channel over said relieved portion, said tie-engaging portion

tion being slotted to form upper and lower jaws adapted to embrace the rail base flange at a point longitudinally remote from said channel.

8. A rail anchor comprising a shoe member adapted to be formed from a generally T-shaped rolled steel section, the T head providing a tie-engaging portion notched to grippingly receive one flange of a rail base, and the T leg being folded to provide a substantially resilient channel portion adapted to grip said rail base flange at a point longitudinally spaced from the tie-engaging portion, and an intermediate portion of the channel being adapted to compressively engage one side only of the rail flange, the remaining channel portions being adapted to be maintained out of contact with the rail flange, and a yoke member adapted to span the rail base having a hook at one end to engage one edge of said base, and a relatively rigid hook at its other end embracing said channel.

ALBERT F. FIFIELD.
